UNITED STATES PATENT OFFICE

ADOLPH A. THOMAS, OF NEW YORK, N. Y.

ELECTRIC PHONOGRAPH REPRODUCER

Application filed December 11, 1926, Serial No. 154,058. Renewed March 8, 1929.

The present invention relates to electric sound-transmitting instruments, and its object is to provide an electric phonograph reproducer of novel construction and improved operation. The reproducer of my invention is particularly adapted to play the new type of record, whether lateral-cut or vertical-cut, in which the spiral track runs to several hundred lines per inch.

10 My new electric reproducer is characterized by utmost simplicity of construction, comprising merely a resistance element and a conducting element, together with a vibratory stylus arm for varying the contact 15 length or area between the two elements. One of these elements is fixed, and the other consists of a resilient strip or flat spring connected at one end to the fixed element. The two elements are properly connected in a battery circuit. The inherent tension of the resilient strip is such that normally it lies in contact with the fixed element for a predetermined length. A stylus arm is at its inner 20 end in engagement with the free end of the resilient strip. When this arm is vibrated in the playing of a record, the resilient strip is vibrated correspondingly and varies the contact length or area between the two elements. In this way, the resistance of the circuit is 25 varied in accordance with the vibrations of the stylus arm, so that electric impulses are set up in the reproducer circuit, and these impulses are utilized to operate loudspeakering mechanism. It is immaterial whether the 30 fixed element or the vibratory spring element is the resistance member. Usually, though, it is more practical to make the spring element of good conducting material and the fixed element of carbon or other material of high 35 electrical resistivity.

In a preferred form of my invention, the fixed element has a curved face with which the resilient strip, fixed at one end, normally lies in contact for a predetermined length or 40 area. The free end of the strip curves away from the contact face of the fixed element and is so connected to the stylus arm that vibrations of the latter exert a substantially tangential push and pull on the spring strip. 45 This operation causes the vibratory move-

ments of the stylus arm to produce amplified variations in contact area or length between the two elements, so that the smallest vibrations of the stylus are sufficient to generate electric impulses in the reproducer circuit. 55

The practical advantages and utility of my new reproducer will become clear from a detailed description of the accompanying drawings, in which I have shown several exemplifications of my invention. In these drawings, 60

Fig. 1 shows in vertical cross-section an electric phonograph reproducer constructed in accordance with my invention;

Fig. 2 is a front view of the device shown in Fig. 1, with the front cover removed;

Fig. 3 is a diagrammatic representation of a modified construction;

Fig. 4 shows in cross-section a reproducer adapted for playing vertical-cut records of the Edison type, the stylus arm being shown 70 in playing position;

Fig. 5 is a view similar to Fig. 4, showing the position of the stylus arm when the same is out of contact with a record; and

Fig. 6 illustrates diagrammatically a simple transmission system between the reproducer and suitable loudspeaker mechanism. 75

Before proceeding with a detailed description of the drawings, I want to make it clear that the various views have been made as simple as possible, with the parts spread out for clearness. The actual devices will be made much more compact than the structures represented in the drawings. 80

Referring to Figs. 1 and 2, there is a suitable casing indicated as a whole by 10, in which the reproducer parts are mounted. This casing, which is small and flat, is usually made of light metal, such as aluminum, and is provided with a hub 11 for attachment to a supporting arm. It will be understood without illustration that the supporting arm is properly mounted for horizontal and vertical movement. In the present instance, casing 10 consists of a central or body portion 90 12, a back-plate 13 and a front plate 14, these parts being secured together by screws 15 to form a dust-proof housing. If desired, the parts 12 and 13 may be formed as a single 95 piece. From the bottom of casing 10 pro-

ject spaced lugs 16 adapted to receive a pair of pivot bearings 17 for a needle arm 18. I might say here when I refer to the member 18 as a needle arm, I include any practical form of stylus arm, irrespective of whether the stylus is in the form of a needle or other record-playing member.

In casing 10 is mounted a resistance member 19, which may simply be a bar of carbon, or made of any other suitable resistance material. The resistance bar 19 is supported in fixed position by insulating lugs 20 secured to the back-plate 13 by screws 21 or otherwise. Any other practical means may be employed for rigidly supporting the resistance member 19 in proper position within the casing. To the lower end of resistance bar 19 is secured a spring strip 22 of good conducting material. A screw 23, or similar means, holds the spring conductor 22 firmly attached to resistance member 19. As seen in Fig. 2, the members 19 and 22 are secured together in alignment. The fastening device 23 is of such a nature that it prevents turning of the spring 22. A conductor 24 is connected to one end of resistance member 19, and a conductor 25 is connected to the other end of the resistance member and also to the attached end of spring conductor 22.

The needle arm 18 is at its inner end provided with a lateral projection or nose-piece 26 adapted to engage the free end of spring conductor 22. A spring 27, secured at one end to the front plate 14 of the casing, bears against the needle arm 18 to counterbalance the effect of contact spring 22 on the needle arm. In other words, the two springs 22 and 27 oppose each other and normally hold the needle arm in a neutral or balanced position, as indicated in Fig. 1.

The operation of the reproducer above described is as follows: Assuming the needle to be in record-playing position, when the inner end of the needle arm moves to the left (as viewed in Fig. 1), the conducting spring 22 is forced toward the fixed resistance member 19, whereby the contact area or length between the members 19 and 22 is increased. Since the member 22 is of good conducting material, it decreases the resistance of the circuit proportionately to the increased contact surface between the members 19 and 22. In Fig. 1, the dotted line 22^a represents roughly the position of the spring contact 22 when the inner end of needle arm 18 has moved toward the left. Now, when the needle arm moves in the opposite direction against the tension of spring 27, (that is, toward the right as viewed in Fig. 1), the spring conductor 22 automatically moves away from the resistance bar 19, as roughly indicated by dotted line 22^b. This means that the resistance of the circuit is increased by an amount depending upon the extent of movement of spring contact 22. The in-

herent tension of this resilient conductor is such that it normally tends to move away from the resistance bar 19. The free ends of needle arm 18 and spring conductor 22 are always in contact, although they are not rigidly fastened together.

It will be clear from the preceding description that the resistance variations of the circuit including the resistance member 19 are in accordance with the vibrations of the needle arm 18. To put this differently: the vibrations of the needle arm cause the contact spring 22 to short-circuit a variable portion of resistance 19, thereby setting up current impulses in the reproducer circuit. Fig. 1 plainly shows that the vibrations of the stylus point 28 are transmitted to the inner end 26 of the needle arm in amplified relation, so that the smallest movements of the stylus are sufficient to produce vibration of the resilient conductor 22 for causing variations of resistance in the reproducer circuit. These resistance changes, as already stated, produce corresponding current impulses in the battery circuit, and these impulses are amplified by suitable apparatus to operate a loudspeaker. Inasmuch as amplifying transmission circuits for electric phonographs are well understood, I need not go into tedious details concerning the same, especially since my invention has nothing to do with any particular type of amplifier. It is sufficient that in Fig. 6 I have indicated a battery 29, a step-up transformer 30, an electromagnetic driving unit 31, and a cone diaphragm 32. Amplifying tubes may be inserted, if necessary, depending upon the type of loudspeaker to be operated. The part 31 may therefore be considered as any suitable apparatus for amplifying the current impulses of the battery circuit to a sufficient degree for actuating the loudspeaking diaphragm 32.

In the diagrammatic representation of Fig. 3, the curved line 33 represents the contact surface of a fixed resistance member, which may be a curved bar of carbon or constructed of any other resistance material suitable for this purpose. Current leads 34 are connected to opposite ends of resistance member 33 for including the same in a battery circuit. A spring strip 35 of good conducting material is connected at point 36 to resistance member 33. The free end 37 of spring conductor 35 is connected to the inner end of needle arm 18. The normal position of spring conductor 35 and needle arm 18 is shown in full lines in Fig. 3. When the needle arm moves into the position 18^a, the spring conductor 35 is forced into increased contact with the resistance element 33, as roughly indicated by dotted line 35^a, and the resistance of the circuit is correspondingly decreased. When the needle arm vibrates into the position indicated by dotted line 18^b,

it pulls the spring contact 35 away from the fixed resistance member 33 into a position indicated approximately by the curved dotted line 35^b. In this last-named position of the parts, the resistance of the circuit is increased.

It will be noticed that in Fig. 3 the needle arm 18 exerts a tangential push and pull on the arcuate contact spring 35, and this action results in an amplified movement of the spring, with correspondingly amplified variations of resistance. To make this clear, let us suppose that, when the arm 18 and contact spring 35 are in normal position, the spring lies in contact with resistance member 33 from point 36 to point *x*. This may be said to determine the normal resistance of the battery circuit. We shall further assume that the dotted-line positions of the parts 18 and 35 in Fig. 3 represent the maximum amount of movement to either side of normal position. When the needle arm vibrates to position 18^a and pushes the contact spring 35 into position 35^a, the contact length between the members 33 and 35 has been increased to point *y*. The resistance of the circuit is now a minimum, on the assumption above made. When the needle arm swings to position 18^b, contact spring 35 engages the resistance member 33 only from point 36 to point *z*, and the circuit resistance is now a maximum. If the positions 18^a and 18^b of the needle arm are at equal distances from the central or normal position, the increased contact length or area represented by the arc *x*—*y* is substantially equal (theoretically, at least) to the decreased contact length represented by the arc *x*—*z*. Between the extreme points *y* and *z* an almost infinite number of resistance variations are possible to represent all movements of the stylus point.

The construction of Fig. 3 is particularly adapted for use on the new style of long-playing record, in which the needle track is several hundred lines to the inch. The smallest vibrations of the stylus point are sufficient to produce vibratory movements of the resilient conductor 35 to vary the resistance of the circuit. As indicating the greatly amplified transmission ratio between the stylus point 28 and spring conductor 35, it will be seen in Fig. 3 that when the stylus travels through the minute arc between points 28 and 28^a, the resistance variation of the circuit is represented by the comparatively long arc *x*—*y*. Thus, theoretically speaking, the amplifying effect produced by the construction of Fig. 3 is represented by the ratio of arc *x*—*y* to arc 28—28^a. In actual practice, of course, one may expect deviations from these theoretical considerations, but the principle of the invention remains. I need hardly explain that the various positions of the parts as indicated by dotted lines in Fig. 3 are not to be regarded as mathematically correct, but rather as approximate visual indications of

the movements of needle arm 18 and spring conductor 35. The maximum vibrations of these parts are very much smaller than would appear from Fig. 3. Since the needle arm 18 is connected to spring conductor 35, the latter also acts as a centering spring for the needle arm and no additional spring is required for that purpose, thereby increasing the simplicity of this device.

The modification of Figs. 4 and 5 shows an adaptation of the invention to vertical-cut records of the Edison type. As is well known, these records are played by a stylus usually in the form of a diamond point which moves in a vertical plane. In Figs. 4 and 5, there is a suitably shaped casing 38 supported in vertical position by an arm 39, which is mounted to swing horizontally and also in a vertical plane. From the bottom of casing 38 extend a pair of lugs 40, between which is pivoted a stylus arm 41 at point 42. The forward end of arm 41 is provided with a head 43 carrying a stylus 44 adapted to operate in a record groove. The inner or rear end of arm 41 has a vertical extension 45 projecting into the casing through a slot 46. A resistance member 47 is mounted in fixed position within the casing 38, as by means of insulating studs 48. Circuit conductors 49 are connected to the opposite ends of resistance member 47. A spring blade 50 of good conducting material is connected at 51 to one end of resistance member 47. The other end of spring contact 50 is connected at 52 to the inner end of extension 45. The inherent tension or resiliency of spring conductor 50 is such that normally it tends to lie against the resistance strip 46, so that the stylus arm 41 is normally held in the position shown in Fig. 5. The contact of the stylus arm with the bottom of the casing at point 53 limits the upward movement of the rear portion of the stylus arm under the action of spring 50. When the stylus point 44 is placed on a record, the weight of the reproducer automatically causes the stylus arm 41 to assume an approximately horizontal position against the normal tension of spring 50, which is now about halfway in contact with resistance element 47. This position of the parts is shown in Fig. 4. As the stylus arm 41 vibrates, the contact area or length between members 47 and 50 is correspondingly varied to produce current impulses in the battery circuit, as already explained. The spring 50 not only causes resistance variations in accordance with the movements of the stylus, but it also acts to hold the stylus arm in a balanced or floating condition during the playing of a record. This produces an exceedingly sensitive instrument, which is instantly responsive to the minutest vibrations of the stylus point. In Figs. 4 and 5, as in Fig. 3, the action of the stylus arm is to exert a substantially tangential push and pull on the connected con-

tact spring, so that what has been said about Fig. 3 applies to Figs. 4 and 5.

I would call special attention to the utter simplicity of my new electric reproducer.

5 There is no magnet, no coil and no chamber filled with carbon granules. I have only a resistance element, a conducting element, and a stylus arm. This simple construction makes it possible to manufacture the device

10 at a correspondingly low cost. The absence of a magnet reduces the weight or pressure at the stylus point, so that the most delicately grooved records can be played without danger of mechanical injury to the frail walls

15 of the groove. Then, too, by doing away with a magnet and its vibratory armature, I eliminate all magnetic drag or bias exerted on the stylus arm in electromagnetic reproducers of prior construction. In my new

20 reproducer, the vibratory contact spring offers just the proper load or mechanical resistance to the stylus and is always free to respond accurately to the stylus vibrations.

An important feature of my invention lies 25 in the fact that identical movements of the stylus produce identical variations of resistance and thereby identical current impulses, as will be understood from the description of Fig. 3. In other words, the same tones are

30 always reproduced in the same way—assuming, of course, that the other parts of the complete reproducing mechanism are in proper working condition. In the case of the old microphone reproducers, the same

35 vibrations of the needle arm cannot produce exactly the same changes of resistance, because the carbon granules are never twice in the same position. Furthermore, the movements of the packed granules against and

40 over each other, pell-mell, tend to produce an electrical disturbance resulting in what is known as microphone noises. These are said to be due to the rubbing or grinding action of the vibratory granules against each

45 other. Now, in my reproducer this objection does not exist, because the vibratory controlling element engages the fixed element in a smooth rolling contact wholly devoid of friction.

50 Although I have described the fixed elements 19, 33 and 47 as resistance members, and have referred to the vibratory elements 22, 35 and 50 as good conductors, it is obvious that the first-mentioned members may

55 be made of good conducting material and the vibratory members may be constructed of resistance material. In practice it is more convenient to mount the resistance member in fixed position, but the alternative arrange-

60 ment comes within the scope of my invention. The resistance members, as already stated, may consist of carbon, as probably the most convenient material to use, but any other high-resistance material may be employed.

65 There are several high-resistance alloys

adapted for use in this invention. The resilient conductors may be of brass, spring steel, or other resilient metal of low electrical resistance. The size and shape of the two co-operating elements will naturally vary in different cases, and the most suitable dimensions of the parts can be determined only by actual tests and trials in any given design of instrument. These things are within the skill of the mechanic.

The particular constructions shown in the drawings are to be regarded merely as illustrative embodiments of my invention and not in the nature of limitations or restrictions, unless so expressed in the claims which follow. Although I have shown and described my invention as a phonograph reproducer, it is evident that it may be constructed as a telephone transmitter by substituting an acoustic diaphragm for the needle arm and make other obvious changes in the design. This will be understood without further explanation.

I purposely do not herein claim broadly the idea of an electric sound transmitter or reproducer in which a pair of elements having different electric conductivities are mounted to have variable contact with each other, and having a vibratory member connected to one of said elements to short-circuit a variable length or area of the element having the lower conductivity. That fundamental concept is covered in my copending application, Serial Number 154,059, filed December 11, 1926.

I claim as my invention:

1. An electric phonograph reproducer comprising a casing adapted to be supported in operative relation to a record, a resistance element and a conducting element carried by said casing and adapted to be connected in circuit, means for rigidly supporting one of said elements, the other element consisting of a resilient strip fixed at one end only so as to be in permanent contact with the fixed element at that end, the inherent tension of said strip being such that normally it lies in contact with said fixed element for a predetermined length and then bends away from said fixed element, and a vibratory stylus arm mounted on said casing and adapted to actuate the movable portion of said resilient strip to vary the contact area between said elements, whereby the resistance of said circuit is varied in accordance with the vibrations of said arm.

2. An electric phonograph reproducer comprising a casing adapted to be supported in operative relation to a record, a resistance element mounted in fixed position in said casing and adapted to be connected in circuit, a resilient conducting strip supported only at one end in said casing so as to be in permanent contact with said element at that end, the inherent tension of said strip being such that normally it lies in contact with said element

for a predetermined length and then bends away from said element, and a vibratory stylus arm mounted on said casing and adapted to actuate the movable portion of said strip to vary the contact area between said element and said strip, whereby the resistance of said circuit is varied in accordance with the vibrations of said arm.

3. An electric phonograph reproducer comprising a resistance element and a conducting element adapted to be connected in circuit, means for rigidly supporting one of said elements, the other element consisting of a curved resilient strip fixed at one end only so as to be permanently connected with the fixed element at that end, the inherent tension of said strip being such that normally it lies in contact with said fixed element for a predetermined length and then gradually curves away from said fixed element, and a stylus member connected to the free end of said strip so as to exert a substantially tangential push and pull on said strip, whereby the vibratory movements of said strip at its free end produce amplified variations in contact area between said two elements.

4. An electric phonograph reproducer comprising a resistance element having a curved contact face, means for supporting said element in fixed position, a curved resilient strip of good conducting material supported at one end in permanent contact with said element, the inherent tension of said strip being such that normally it lies in contact with the curved face of said element for a predetermined length and then gradually curves away from said face, means for connecting said resistance element in circuit, and a stylus member connected to the free end of said strip so as to exert a substantially tangential push and pull on said strip, whereby the vibratory movements of said strip at its free end produce amplified variations in contact area between said element and said strip.

5. An electric phonograph reproducer comprising a casing, a resistance element fixed in said casing and adapted to be connected in circuit, a resilient conducting strip supported only at one end so as to be in permanent contact with said element at that end, the inherent tension of said strip being such that normally it lies in contact with said element for a predetermined length and then bends away from said element, and a stylus arm pivoted to said casing and at its inner end engaging the free portion of said strip, whereby the resistance of said circuit is varied in accordance with the vibrations of said arm, which is so pivoted that its inner end vibrates in amplified relation to the vibrations of the stylus.

6. An electric phonograph reproducer comprising a casing, a resistance element and a conducting element adapted to be

connected in circuit, means for rigidly supporting one of said elements in said casing, the other element consisting of a curved resilient strip fixed at one end only so as to be permanently connected with the fixed element at that end, the inherent tension of said strip being such that normally it lies in contact with said fixed element for a predetermined length and then gradually curves away from said fixed element, and a stylus arm pivoted to said casing and connected at its inner end to the free end of said strip so as to exert a substantial tangential push and pull on said strip, whereby the vibrations of said needle arm produce amplified resistance variations between said two elements and thereby generate current impulses in said circuit.

7. An electric phonograph reproducer comprising a casing, a resistance element rigidly mounted in said casing and adapted to be connected in circuit to control loud-speaker mechanism, said element having a curved contact face, a curved resilient strip of good conducting material connected at one end to said element and free at its other end, the inherent tension of said strip being such that normally it lies in contact with the curved face of said element for a predetermined length and then gradually curves away from said face, and a stylus arm pivoted to said casing and connected at its inner end to the free end of said strip so as to exert a substantially tangential push and pull on said strip, whereby the vibrations of said arm produce amplified resistance variations between said element and said strip and thereby generate current impulses in said circuit.

8. In an electric phonograph reproducer adapted to play vertical-cut records, a casing provided with a vibratory resilient strip fixed at one end, a substantially horizontal stylus arm pivoted to said casing so as to vibrate in a vertical plane and connected to the free end of said strip, and means whereby the vibratory movements of said strip produce current impulses in a reproducer circuit, said resilient strip sustaining the stylus arm in floating condition during record-playing operation and also holding said arm in predetermined idle position on the casing.

9. An electric phonograph reproducer for playing vertical-cut records, comprising a casing adapted to be supported on a movable arm, a resistance element rigidly mounted in said casing, said element having a curved contact face, a curved resilient strip of good conducting material connected at one end to said element and free at its other end, said strip being so mounted as to vibrate in a vertical plane, the inherent tension of said strip being such that normally it lies in contact with the curved face of said element for

- a predetermined length, a substantially horizontal stylus arm pivoted to said casing so as to vibrate in a vertical plane, means for connecting the rear end of said stylus arm to the free end of said resilient strip, whereby said arm exerts a substantially tangential push and pull on said strip to vibrate the same and thereby vary its contact length with said resistance element, and means for so connecting said element and contact strip in a reproducer circuit that the vibratory movements of said strip produce current impulses in said circuit, said resilient strip sustaining the stylus arm in floating condition during recording 5
- 11 playing operation and also holding said arm in predetermined idle position on the casing.
10. An electric phonograph reproducer comprising a casing adapted to be supported in operative relation to a record, a high-resistance member mounted in said casing and adapted to be connected in circuit, a low-resistance member arranged in said casing in contact with said first-named member, means for supporting one of said members in fixed 20
- 25 position, and a stylus arm carried by said casing for operating the other member to cause said low-resistance member to short-circuit a variable portion of said high-resistance member in accordance with the vibrations of said 30 arm.
11. An electric phonograph reproducer comprising the combination of a curved spring strip of conducting material supported at one end, a resistance member rigidly 35
- 40 mounted to have variable contact with said curved strip, and a stylus for vibrating said strip to short-circuit a variable length or area of said member, the inherent resiliency of said spring strip automatically holding said stylus in predetermined normal position.
12. An electric phonograph reproducer comprising a movable spring conductor of relatively low resistance mounted for vibratory movement, a stationary resistance member arranged to have variable contact with said spring conductor, and a stylus for vibrating said conductor to short-circuit a variable length or area of said resistance member, the inherent resiliency of said spring 45
- 50 conductor automatically holding said stylus in predetermined normal position.
13. An electric phonograph reproducer comprising a pair of elements having different electric conductivities, means for rigidly 55
- 60 supporting one of said elements, means for movably supporting the other element so as to have variable contact with the fixed element, said movable element being inherently elastic and self-restoring, and a stylus connection for vibrating said movable element to short-circuit a variable length or area of the element having the lower conductivity, said movable elastic element being adapted to automatically restore said stylus connection to normal 65

14. An electric phonograph reproducer comprising a pair of elements having different electric conductivities, means for rigidly supporting one of said elements, means for movably supporting the other element so as to have variable contact with the rigid element, said movable element being inherently elastic and self-restoring, and a vibratory stylus member for operating said movable element to short-circuit a variable length or area of the element having the lower conductivity, said movable elastic element being adapted to automatically restore said stylus member to normal position. 70
15. An electric phonograph reproducer comprising a fixed member provided with a contact surface, a movable spring member mounted to have variable contact with the surface of said fixed member, one of said members being of relatively low conductivity and the other member being of relatively high conductivity, and a stylus for vibrating said spring member to vary the contact area between said members, said spring member automatically restoring said stylus to predetermined normal position. 75
